FLUORESCENT LIGHTING FIXTURE

Matthew Murino, New York, N. Y.

Application April 30, 1947, Serial No. 744,896

2 Claims. (Cl. 173—328)

1

This invention relates to fluorescent lighting fixtures.

It is an object of the present invention to provide an end bracket carrying contact terminal for delivering current to a fluorescent tube which is supported from the same which is divided in two parts and so constructed that the parts can be separated and such wherein that one of the parts is broken only the one part need to be replaced.

Another object of the present invention is to provide a bracket for supporting a fluorescent lamp which cannot be easily broken and which will permit the attachment of the fluorescent lamp to one of its parts so that the part may be in turn connected to the fixed part of the bracket whereby in difficult locations the mounting of the lamp may be facilitated.

For other objects and for a better understanding of the invention, reference may be had to the following detailed description taken in connection with the accompanying drawing, in which

Fig. 1 is a fragmentary view of a fluorescent lamp connected with the bracket embodying the features of the present invention.

Fig. 2 is a cross-sectional view taken on line 2—2 of Fig. 1.

Fig. 3 is a cross-sectional view taken on line 3—3 of Fig. 2.

Fig. 4 is a fragmentary and cross-sectional view of a modified form of bracket construction.

Fig. 5 is a collective view of the coupling parts of the bracket shown in Fig. 4.

Fig. 6 is a rear elevational view of the bracket construction shown in Fig. 4 and illustrating the manner in which the parts are disposed to connect them together.

Fig. 7 is a top plan view of the screw contact terminal.

Fig. 8 is a side elevational view of the terminal and taken on line 8—8 of Fig. 7.

Referring now to the figures, 10 represents a base having a fixed part 11 of a bracket thereon. This fixed part 11 has a dovetail groove 12 in its front face for receiving a dovetail projection 13 of a separable bracket part 14. The bracket part 11 has openings or chambers 15 therein in which there are spring pressed terminal elements 16 adapted to project through the front of the bracket and into the dovetail groove 12 thereof. These terminals 16 will engage with heads 17 of screws extending from the rear of the front bracket part 14. These heads 17 are hollowed or provided with a hole 18 for receiving the rounded end of the terminals 16. A slot 19 is provided

on the head for the attachment thereto of a screw driver. The hole 18 is not disposed at the same depth as the slot 19 so that the end of the screw driver will have engagement throughout the entire length of the slot 19. Extending from the heads 17 of the screw is a shank 21 which is threadingly connected to a spring clip terminal 22 which has a bent portion 23 for receiving a pin 24 of a fluorescent tube 25. The forward end of the bracket part 14 has the usual opening 26 through which the pins 24 are extended for engagement with the contact portions 23 of the contact spring 22.

It will be apparent that when the bracket part 14 is slid downwardly so that its dovetail projection 13 is received in the dovetail groove 12 of the bracket part 11 that an engagement will be made of the pin terminals 16 with the holes in the heads 17. By this engagement the bracket will be rigid and become a unitary structure. The bracket part 14 will be retained against further sliding movement by the contacts or terminals themselves and at the same time a good circuit connection is established.

25 Referring now particularly to Figs. 4, 5, and 6, there is shown a modified form of bracket where there is a bracket part 27 having a central projection 28 thereon with pins 29 extending laterally therefrom and adapted to receive a sleeve 31 with bayonet slots 32 therein. The sleeve 31 is contained in a bracket part 33 having contact screws 34 therein with heads constructed in the manner shown in Figs. 7 and 8.

To connect the parts 33 and 27 together, the projection 28 is centered in the sleeve 31 and the part 33 turned relative to the part 27 so that screws 34 are brought into contact with spring pressed contact pins 35 of the part 27. The forward end of the part 33 is of similar construction to that shown in Fig. 2.

While various changes may be made in the detailed construction, it shall be understood that such changes shall be within the spirit and scope of the present invention as defined by the appended claims.

Having thus set forth and disclosed the nature of this invention, what is claimed is:

1. A bracket mounting for a fluorescent lamp comprising a base, a two part end bracket extending from the base and adapted to receive the fluorescent lamp, one part of the bracket being fixed to the base, having spring biased pin terminals, the other part being separable from the one part and having contact terminals adapted 50 to engage respectively with the spring biased pin

terminals, means for releasably securing the parts together including the provision of a dovetail groove on one part and a dovetail projection on the other part adapted to slidably engage with the dovetail groove, spring clipped terminals within the one part for receiving the end terminal of the fluorescent lamp, the contacts being in the forms of screws extending through the bracket part for retaining the spring clipped terminals and having heads with openings therein for receiving the ends of the spring biased pins of the one part, whereby the parts will be retained against displacement from one another.

2. A bracket mounting for fluorescent lamps comprising a base, a two part separable bracket mounted on the base and adapted to receive the end terminal of a fluorescent lamp, one of the parts having spring pressed pin terminals, the other part having screw terminals with heads which are hollowed to receive the ends of the pin terminals whereby to prevent the displacement of

the parts from one another when connected together, the said parts having guiding means extending between the same for causing the same to be fitted together in tight engagement with one another, the pin terminals engaging with the screw heads at the end of the fitting movement.

MATTHEW MURINO.
